(57) **CLAIM**

The ornamental design for a water bottle, as shown and described.

DESCRIPTION

FIG. 1 is an isometric view of a water bottle; FIG. 2 is another isometric view of the water bottle; FIG. 3 is a front view of the water bottle of FIG. 1; FIG. 4 is a rear view of the water bottle of FIG. 1; FIG. 5 is a left-side view of the water bottle of FIG. 1; FIG. 6 is a right-side view of the water bottle of FIG. 1; FIG. 7 is a top view of the water bottle of FIG. 1; and, FIG. 8 is a bottom view of the water bottle of FIG. 1. The broken lines represent portions of the water bottle that form no part of the claimed design.
